UNITED STATES PATENT OFFICE.

HERMAN W. SCHATZ, OF NORWOOD, AND AUGUSTUS M. SOSA, OF CINCINNATI, OHIO,
ASSIGNORS TO THE AMERICAN TOOL WORKS COMPANY, OF CINCINNATI, OHIO, A
CORPORATION OF OHIO.

DRILLING MACHINE.

1,413,790.

Specification of Letters Patent. Patented Apr. 25, 1922.

Application filed September 10, 1917. Serial No. 190,652.

To all whom it may concern:

Be it known that we, HERMAN W. SCHATZ and AUGUSTUS M. SOSA, citizens of the United States, residing, respectively, at Norwood and at Cincinnati, in the county of Hamilton and State of Ohio, have jointly invented certain new and useful Improvements in Drilling Machines, of which the following is a specification.

10 Our invention relates to drilling machines employing means for raising and lowering the drill-arm on the column or standard.

It is the object of our invention to provide a drilling machine with an electric motor 15 mounted on the drill-arm, and arranged for causing operation of the raising and lowering means for the drill-arm; and, further to provide an arrangement of means whereby the drill-spindle may be operated and the 20 raising and lowering of the drill-arm be effected by means of a single electric motor supported by a movable drill-arm.

The invention will be further readily understood from the following description and 25 claims, and from the drawings, in which latter:

Fig. 1 is a rear elevation of a radial drilling machine embodying the invention, parts being broken away.

30 Fig. 2 is a plan view of the same, partly in horizontal section on the line 2—2 of Fig. 1.

Fig. 3 is a plan view of our improved device, partly broken away, and with the gear-cover at the top of the column removed.

Fig. 4 is a vertical cross-section of the same taken on the irregular line 4—4 of Fig. 3.

Fig. 5 is a vertical sectional detail, taken 40 on the line 5—5 of Fig. 2.

Fig. 6 is a vertical sectional detail, taken on the line 6—6 of Fig. 2.

Fig. 7 is a detail in cross-section, taken on the line 7 of Fig. 3; and,

45 Fig. 8 is a detail in vertical section, taken on the line 8—8 of Fig. 2.

In the present exemplification of the invention, a radial drilling machine is shown. The drilling machine exemplified comprises 50 a base 11, from which a post 12 extends vertically, a column 13, shown as a rotary column, being rotatable about the post in usual or suitable manner, and arranged to be clamped in adjusted positions with relation

to the base by means of the usual clamp, instances at 14. A drill-arm 16 has a bearing 17 about the column, the bearing being arranged to be raised and lowered to suitable elevation on the column for positioning the drill-arm at suitable elevation for proper 60 operation of the drill with relation to the work arranged to be supported on a suitable bed 18. The bearing is arranged to be clamped about the column, when the same has been adjusted, for instance, by means 65 of a usual or suitable clamp 19.

The drill-arm is arranged to have a tool-slide 21 adjustable laterally thereon on suitable guideways 22 on the arm, the lateral movement of the slide being accomplished 70 in any well-known manner. The slide has a usual drill-spindle 25 journaled therein.

An operating shaft 26 for operating the drill-spindle extends lengthwise of the drill-arm. Suitable operating means for driving 75 and feeding the drill-spindle are mounted on the tool-slide, and have operative connection with the operating shaft. These operating means may be of any usual or ordinary construction, and may include a pair 80 of bevel-gears 27, 28, having suitable spline-connection 29 with the operating shaft, suitable clutches operated by a shifting-lever 30, being arranged to operatively connect a bevel-gear 36 selectively through either of 85 said bevel-gears 27, 28, with the operating shaft, for selectively rotating the bevel-gear 36 in reverse directions, the latter being connected with a train of gearing, indicated at 37, for operating the drill-spindle. 90

The means for raising and lowering the drill-arm on the column are exemplified as a screw-rod 41, extending lengthwise of the column, with which a nut 42 has threaded engagement. The nut is exemplified as located in a recess 43 of a lug 44 on the drill-arm, a ledge 45 of the latter having support on said nut, a set-screw 46 preventing rotation of the nut. The lower end of the screw-rod is journaled in a bearing 47 in the lower part of the column, and the upper end of the screw-rod is journaled in a bearing 48 of a cap 49 secured to the upper end of the column. 95

A bracket 51 extends from the drill-arm 105 bearing 17 at that side of said bearing opposite the side thereof from which the drill-arm 16 projects. An electric motor 52 is

supported by said bracket, being exemplified as secured thereto by bolts 53. The armature-shaft 54 of the electric motor has a pinion 55 fast thereon, which meshes with 5 a gear 56.

A gear-support 61 is secured to the bracket, as by means of bolts 62. The gear-support forms an oil-cap which is arranged to contain a body of oil in which the pinion 55 and gear 56 are received. The gear-support has a bearing 63 thereon for the 10 armature-shaft 54 of the electric motor.

Bearings 64 are located on the gear-support and have a sleeve 65 journaled therein, 15 the gear 56 being secured to said sleeve, as by a key 67. Said sleeve also has a bevel-gear 68 thereon. The sleeve is exemplified as an extended hub of said bevel-gear. The sleeve receives the end of the operating shaft 20 26, which is fixed thereto so as to rotate therewith, by means of a key 69.

The bevel-gear 68 meshes with a bevel-gear 71, which has fixed therewith a spur-gear 72, as by having the spur-gear received 25 about the hub 73 of the bevel-gear 71, a key 74 fixedly connecting the gears. The bevel-gear 71 and spur-gear 72 are journaled about a stud-shaft 75, fixed by a set-bolt 76 in a bearing 77 on a lug 78 extending from 30 the gear-support.

The spur-gear 72 meshes with a spur-gear 79 which has a hub 80 journaled in a bearing 81 in said lug of the gear-support, a collar 82 fixed to said hub, for instance, by 35 a set-screw 83, acting with the gear 79 to hold said hub lengthwise to said bearing 81 for compelling movements of the gear 79 with the drill-arm.

An upright shaft 86 extends lengthwise 40 of the column and is journaled at its lower end in a bearing 87 on the rotatable column and is journaled at its upper end in a bearing 88 in the cap 49. The gear 79 has spline-connection 89 with said upright shaft 86 45 for rotating said upright shaft throughout the adjustments to the various elevations into which the drill-arm may be positioned.

The shaft 86 has a gear 91 fixed thereto. The gear 91 meshes with a gear 92 fixed 50 with a gear 93 to rotate about a stud-shaft 94, secured in a bearing 95 in the cap 49, as by means of a set-screw 96. The gears 92, 93, are fixed together, as by a key 97, and are held on the stud-shaft by a washer 55 98 and nut 99, the washer impinging a shoulder 100 on said shaft.

The gear 92 meshes with the gear 101, which is fixed to a gear 102, as by a key 103. The gears 101, 102, rotate about a stud-shaft 104, fixed in a bearing 105, as by 60 clamping said shaft in said bearing between a shoulder 106 on said shaft and a clamp-nut 107. Gears 101, 102, are held on said stud-shaft by means of a washer 108 and a 65 nut 109 clamping said washer against a

shoulder 110 on said shaft, permitting said gears to rotate between said washer and the bearing 105.

A rocker-lever 112 is journaled about a journal-extension 113 of the bearing 48 at 70 the upper end of the screw-rod. The screw-rod has a gear 114 fixed at its upper end. A collar 115 about the screw-shaft under the bearing 48 is fixed to the screw-shaft. The pivotal axis of the rocker-lever and the axes 75 of rotation of the screw-rod and gear 114 are coincident. The rocker-lever has a pinion 117 journaled about a stud-shaft 118 secured to the arm 119 of the rocker-lever. The rocker-lever is arranged to have lateral motion imparted thereto, accomplished by providing the arm 120 thereof with a segment-rack 121 engaged by a segment-rack 122 secured to the upper end of a rock-shaft 123, extending lengthwise of the column, and journaled at its upper end in a bearing 124 on the cap 49, and at its lower end in a suitable bearing 125 adjacent the lower end of the column. The rock-shaft is provided with a handle 126 by means of 80 which the rocker-lever 112 is moved from side to side.

Upon the lateral movement of the rocker-lever, the pinion 117 is caused to selectively mesh with the gear 93 or the gear 102 depending on the direction of movement of the rocker-lever, the gears 93, 102, rotating in opposite directions, and thereby rotating the gear 116 selectively in opposite directions for imparting similar selective directions of rotation to the screw-rod 41. When the pinion is in intermediate position and out of mesh with both gears 93, 102, the screw-rod is non-rotating. The gears 93, 102, act as driving gears rotating in opposite directions for rotating the screw-rod in 95 opposite directions upon selective engagement of the pinion with said respective gears 93, 102.

In order to control the meshing relation 110 of the pinion 117 with the gears 93, 102, stops 127, exemplified as bolts are arranged to coact with stop-faces 128 on the cap 49, the said bolts being axially adjustable in lugs 129 extending from the segment-rack 115 122, the bolts being fixed in adjusted positions by means of nuts 130.

By means of our improved device a single electric motor, supported directly by the drill-arm, is arranged to operate both 120 the means for operating the drill-spindle and the raising and lowering means of the drill-arm, by means direct connected with both said means, forming a compact and simple structure.

If desired a speed controller or commutator, exemplified at 131, for controlling the speeds of the electric motor, may be mounted on the drill-arm, being exemplified as secured to the motor-frame by screws 132. 130

Having thus fully described our invention, what we claim as new and desire to secure by Letters Patent, is:

1. In a drilling machine, the combination 5 of an upright post, an upright column journaled in upright relation about said post, a drill-arm structure including a drill-arm, means for rotatively adjusting said column about said post, a screw-rod having connection with said drill-arm structure for adjusting the latter to elevation on said column, a shaft extending up and down having operative connection with said screw-rod, and an electric motor supported by said drill-arm 10 structure movable up and down and to radial positions with said drill-arm structure and having operative connection with said shaft for rotating the same during adjustments to elevation of said drill-arm structure.
2. In a drilling machine, the combination 15 of an upright post, an upright column rotatable in upright position about said post, a drill-arm structure including a drill-arm adjustable up and down on said column, means for adjusting said drill-arm structure with said column about said post, a tool-slide adjustable laterally on said drill-arm, a drill-spindle thereon, a shaft extending lengthwise of said drill-arm for operating said drill-spindle at the various lateral positions 20 of said tool-slide, raising and lowering means comprising a rotatable element for adjusting said drill-arm structure up and down on said column, an electric motor movable with said drill-arm structure for different elevations and radial positions of said drill-arm, and driving connections between said electric motor and said shaft and said rotatable element respectively, said shaft and rotatable element having their axes of 25 rotation at substantial right angles to each other.
3. In a drilling machine, the combination 30 of an upright post, an upright column rotatable in upright position about said post, a drill-arm structure including a drill-arm adjustable up and down on said column, means comprising a rotatable element for adjusting said drill-arm structure up and down on said column, an electric motor movable with said drill-arm structure for different elevations and radial positions of said 35 drill-arm, and driving connections between said electric motor and said shaft and said rotatable element respectively.
4. In a radial drill press, the combination 40 of a base, a column supported thereby, an arm carried by the column and movable vertically along the same, a spindle head carried by the arm and movable laterally along the same, a rotary spindle carried by the spindle head, a driving shaft extending along the arm, and transversely past the column, and driving devices by which said shaft may rotate the spindle and move the arm vertically on the column, the motor and spindle head being carried by the arm on opposite sides of the column.

In testimony whereof, we have hereunto signed our names in the presence of two subscribing witnesses.

HERMAN W. SCHATZ.
AUGUSTUS M. SOSA.

Witnesses:

ALBERT L. JENNINGS,
ALLEN A. EDWARDS.

drill-arm structure including a drill-arm adjustable up and down on said column, means for adjusting said drill-arm structure with 45 said column about said post, a tool-slide adjustable laterally on said drill-arm, a drill-spindle thereon, a shaft extending lengthwise of said drill-arm for operating said drill-spindle at the various lateral positions 50 of said tool-slide, raising and lowering means comprising a rotatable element for adjusting said drill-arm structure up and down on said column, an electric motor movable with said drill-arm structure for different elevations and radial positions of said 55 drill-arm, and driving connections between said electric motor and said shaft and said rotatable element respectively, said shaft and rotatable element having their axes of 60 rotation at substantial right angles to each other.

4. In a radial drill press, the combination 65 of a base, a column supported thereby, an arm carried by the column and movable vertically along the same, a spindle head carried by the arm and movable laterally along the same, a rotary spindle carried by the spindle head, a driving shaft extending along the arm, and transversely past the column, and 70 driving devices by which said shaft may rotate the spindle and move the arm vertically on the column, the motor and spindle head being carried by the arm on opposite sides of the column.
